(57) **CLAIM**

The ornamental design for a vertical cold finger adapter, as shown and described.

DESCRIPTION

FIG. 1 is a front elevational of a vertical cold finger adapter of the current disclosure.

FIG. 2 is rear elevational view of a vertical cold finger adapter of the current disclosure.

FIG. 3 is right side elevational view of a vertical cold finger adapter of the current disclosure.

FIG. 4 is a left side elevational view of a vertical cold finger adapter of the current disclosure.

FIG. 5 is a top plan view of a vertical cold finger adapter of the current disclosure; and,

FIG. 6 is a bottom plan view of a vertical cold finger adapter of the current disclosure.

The broken lines shown in the figures represent portions of the vertical cold finger adapter that form no part of the claimed design.
